UNITED STATES PATENT OFFICE.

MOSES APPEL, OF JOHNSTOWN, PENNSYLVANIA.

CONDENSER FOR ZINC VAPORS.

1,103,123.

Specification of Letters Patent. Patented July 14, 1914.

Application filed September 25, 1913. Serial No. 791,878.

To all whom it may concern:

Be it known that I, MOSES APPEL, a citizen of the United States, and a resident of Johnstown, in the county of Cambria and State of Pennsylvania, have made certain new and useful Improvements in Condensers for Zinc Vapors, of which the following is a specification.

My invention relates to improvements for condensers in connection with the production of zinc, and it consists in the combinations, constructions, and arrangements herein described and claimed.

An object of my invention is to provide a device which is designed to be used preferably with an electric furnace for condensing the zinc vapors which are driven off by the furnace.

A further object of my invention is to provide a device in which the condensation takes place through the medium of air or gas cooled tubes in which the flow of air or gas can be easily regulated.

Other objects and advantages will appear in the following specification and the novel features of the device will be particularly pointed out in the appended claims.

My invention is illustrated in the accompanying drawings forming part of this application in which—

Figure 1 is a section through a condenser constructed according to my invention, Fig. 2 is a section along the line 2—2 of Fig. 1, Fig. 3 is a vertical section on the line 3—3 of Fig. 4, Fig. 4 is a section on the line 4—4 of Fig. 3, Fig. 5 is a vertical section through a modified form of the device, Fig. 6 is a section at right angles to Fig. 5 through the modified form, and Fig. 7 is a section through another modified form of the device.

The description of this condenser is as used for the condensing of zinc vapor but this type of condenser may also be used for condensing of other metallic or non-metallic vapors, and as a heat recuperator in connection with heating furnaces.

In carrying out my invention I provide an outer metallic shell or casing 1 which is lined with fire brick 2 or other suitable refractory material. At the bottom of the device is an extension 4 (see Figs. 3 and 4) in which is an inlet flue 5 leading from the electric furnace (not shown) or other furnace where the vapors of the zinc are produced. The inlet 5 communicates by means

of laterally extending passages 6 with upwardly extending passages 7. The latter passages are formed between a series of vertical tubes 8 made preferably of fire clay or silica tile. The preferred arrangement of these tubes is that shown in Fig. 2 in which the tubes 8 alternate with the flues 7 in both directions. Each tube 8 has a similar tube 9 leading from it to a passage 10, the latter constituting an air passage and being open at one end for the escape of cooling air or gas.

Communicating with the top of each of the tubes 8 is an inlet pipe 11 which leads from a pipe 12, the pipe 12 in turn communicating with a large pipe 13, which is connected with a fan or blower 14. Each of said passages 10 may be connected to a suitable suction fan or exhaust (not shown). At 15 in Fig. 4 I have shown a tap hole for metallic zinc which may be closed by any suitable closure 16, such as a plug of clay or other suitable material.

From the foregoing description of the various parts of the device the operation thereof may be readily understood.

The zinc vapor coming from the furnace passes through the inlet 5 and into the laterally extending passages 6 and then upwardly. The fan is then set in motion and air is caused to circulate through the cooling tubes 8 in a downward direction or in opposite direction to the flow of metallic vapor. This air then passes through tubes 9 to passages 10. The zinc vapor comes into contact with outside surfaces of cooling tubes 8 and tends to condense in liquid form.

The laterally extending passages 6 are slightly inclined toward the passage 5 and the latter passage is slightly inclined toward the tap hole 15, so that as the zinc is condensed it flows toward the tap hole and may be withdrawn through the latter. It is obvious that the fan can be speeded up to force in more air or the openings into the air tubes 10 may be partially closed by any suitable means such as by the gate 10* shown in Fig. 3. Thus the supply of air may be regulated and hence the device may be adjusted so as to meet the requirements for the most efficient condensation of the zinc vapor. Since the cooling tubes are made of refractory material the device when once regulated is not as apt to get out of order as where the cooling tubes are made of metal which will cool off quickly or heat up

quickly. Thus the device is less subject to variation and requires less adjustment of the cooling medium after the device is started.

5 In Figs. 5 and 6 I have shown a modified form of the device. In this form the metallic shell or casing 1 is lined with fire brick 2. The passages 6 which correspond with those already described communicate with 10 vertical passages 7. Between the adjacent vertical passages 7 are disposed tubes 8 of fire clay or silica tile, closed at their tops and having inlet tubes 8^a, while extending downwardly in the centers of the 15 tubes 8 are pipes 17 which communicate with a common pipe 18 leading to a large outlet pipe 19 similar to the pipe 13 in Fig. 2, and which is designed to communicate with the exhaust (not shown). The tubes 20 in this instance have an opening at the top for admission of cooling air or gas, and air is exhausted from bottom of refractory tubes by means of pipe 17, thence through pipes 18 and 19 to exhaust fan or exhaust 25 apparatus. This obviates the necessity of providing special air chambers and auxiliary tubes such as those shown at 9 in Fig. 1. In this case as in the other the amount of air supplied to the cooling tubes 8 may be 30 regulated so as to secure the maximum efficiency of the device.

In Fig. 7 I have shown a modified form of the device in which the shorter tube is the inlet tube and the longer tube the outlet 35 tube, the air or other gaseous medium passing in an opposite direction to that shown in Fig. 5.

In the condensing of zinc from the state of vapor trouble is experienced due to the 40 condensing of zinc as dust or blue powder. One reason for the condensing of zinc as dust is that the zinc vapor comes into contact with a comparatively cold condensing surface. In zinc condensers in present use 45 there is no method of regulating accurately the supply of air or gas which cools the outside surface. In my type of zinc condenser the vapors are to be condensed by contact with the surfaces of air or gas cooled tubes. 50 The zinc vapors to pass through the condenser in one direction and the air or gas used for cooling purposes to pass through the condenser in the opposite direction. This passing of zinc vapor and cooling air 55 or gas in opposite directions is very important for the following reason. As the cooling air or gas passes in opposite direction to the zinc vapor, the temperature of air or gas will gradually increase as it 60 passes through the condenser from the temperature of air or gas supply at entrance to

very nearly the temperature of the entering zinc vapors on leaving the condenser. Therefore the temperature of the tubes or condensing surfaces for the zinc vapors will gradually increase from a temperature near that of the cooling air or gas supply at the outlet of the condenser to a temperature near that of the entering zinc vapor at the entrance to the condenser. Therefore a condenser of 70 this type when in continuous operation will have ideal conditions for condensing surfaces, in that the zinc vapor will come into contact with condensing surfaces whose temperature gradually decreases from a temperature near that of the zinc vapor to a 75 temperature near that of air or gas supply. Thus in a condenser of this type we will have a minimum formation of zinc dust or blue powder. The amount of cooling air 80 or gas can be regulated to give best conditions for condensation.

It is to be understood that the invention is not limited to the details of construction herein described by way of illustration and 85 that the form, size and proportion of the parts may be varied according to character of material treated and scale of operations.

I claim:—

1. In a condenser for zinc vapors, an 90 outer metallic casing, an inner refractory lining for said casing, a plurality of rows of cooling tubes disposed within said casing, the tubes of each row being spaced apart and the tubes of adjacent rows being in 95 staggered relation, the corners of the tubes of one row abutting the corners of the tubes of the adjacent row, and the space between the tubes constituting passages for zinc vapor, and means for forcing a gaseous cooling 100 medium through the cooling tubes, in an opposite direction to that of the zinc vapor.

2. In a condenser for zinc vapors, an outer metallic casing, an inner refractory 105 lining for said casing, a plurality of vertical rows of cooling tubes disposed within said casing, the tubes of each row being spaced apart and the tubes of adjacent rows being in staggered relation, the corners of the tubes in one row abutting the corners of the tubes in the adjacent row, the space 110 between the tubes constituting passages for zinc vapor, means for introducing zinc vapor at the bottom of the casing, and means 115 for forcing a gaseous cooling medium downwardly through the cooling tubes.

MOSES APPEL.
